UNITED STATES PATENT OFFICE

2,023,933

METHOD OF MAKING A SHEET METAL ARTICLE

August Millinger, Louisville, Ky.

Application October 27, 1932, Serial No. 639,869

1 Claim. (Cl. 153—21)

My invention relates to a novel method of cutting, forming and making a sheet metal article having a longitudinal slot, flanged edges on three sides, and a tongue projecting from one end, 5 with male and female dies.

The invention consists of a combination of cutting, punching and forming dies of which a typical embodiment is illustrated in the accompanying drawing, wherein:

10 Figures 1 and 2 show a perspective view of the male and female dies for cutting, forming and shaping the herein described sheet metal article.

Figure 3 shows a perspective view of the male member of a cutting or slotting die.

15 Figure 4 shows a perspective view of the female member of a cutting or slotting die, companion to Figure 3.

Figure 5 shows a perspective view of a cutting die.

20 Figure 6 shows a perspective view of the female member of a cutting die, companion to Figure 5.

Figure 7 shows a perspective view of a finished article of manufacture produced by means of the cutting, slotting and forming dies illustrated in 25 Figures 1—2—3—4—5—6.

Numeral 1 designates the forming member of the male die, 2 a recessed member of the female die, 3 the cutting edge of the male die, 4 the slot in the female die into which 3 is forced, 5

the cutting edges of the die to the recesses into which 5—5 are forced, 7 the flanges which are produced by means of the forming die illustrated in Figure 1, 8 the slot cut by means of cutting edges 3 and 4 of the cutting or slotting dies illustrated in Figures 3 and 4, 9 an extended portion of the article formed by cutting edges 5 and 6.

From the above detailed description of the invention it is believed that the construction, method and operation thereof will at once be apparent, and while there are herein shown and described the preferred embodiments of the invention, it is nevertheless to be understood 15 that minor changes may be made therein without departing from the spirit and scope of the invention as claimed.

I claim:

20 The method of making a sheet metal article having a longitudinal slot, flanged edges on three sides and a tongue projecting from one end, consisting of first flanging the three edges of a plain sheet in rectangular cooperating male and female dies, secondly cutting a longitudinal slot in the center of the flanged sheet and thereafter cutting the tongue portion at the end of the article.

AUGUST MILLINGER.
